UNITED STATES PATENT OFFICE.

HARRY M. HENDERSON, OF WASHINGTON, DISTRICT OF COLUMBIA.

DISPENSING DEVICE.

Application filed May 12, 1925. Serial No. 29,835.

This invention relates to new and useful improvements in dispensing devices, and particularly to devices for dispensing beverages.

5 One object of the invention is to provide a faucet for a beverage dispensing device which will accurately measure a glassful of the beverage without danger of any excess which might run over the glass and onto 10 the hand of the operator.

Another object is to provide a measuring faucet which cannot be manipulated to cause the beverage to continue to flow from the container, thus eliminating possibility of 15 drawing more than a glassful at a single operation.

Another object is to provide a faucet by 20 means of which the settling or pulp of the fruit of the beverage may be stirred up before opening the faucet to draw the beverage, thus permitting the drawing of some 25 of the pulp.

A further object is to provide a faucet which will effectively prevent leakage of the 25 beverage while the faucet is closed.

A still further object is to provide a faucet of this character wherein the manipulation thereof to operate the stirrer will simultaneously grind the joint of faucet and container, whereby to provide a tight joint without the use of the ordinary washers, 30 packing or the like.

Other objects and advantages will be apparent from the following description when 35 taken in connection with the accompanying drawing.

In the drawing:

Figure 1 is a vertical sectional view 40 through a portion of the container showing the valve partly in elevation and partly in section.

Figure 2 is a vertical transverse sectional view on the line 2-2 of Figure 1.

Figure 3 is a rear end view of the valve, 45 showing the agitator.

Referring particularly to the accompanying drawing, 10 represents a portion of a container for holding a beverage, and which has the cast bottom 11. Formed integrally 50 with the bottom, and extending partially across the bottom, and out through the outer wall of the bottom, is a tubular valve casting 12, that portion within the container having the circularly extending elongated 55 slots 13, through which the beverage from the container is adapted to flow into said

bore. Surrounding the outer end of the bore of the casing 12, on the outer face of the bottom, there is formed a flange 14, over which is engaged a cap 15, the outer end of 60

which is formed with a central opening 16, to which reference will be made later herein. Formed on the lower side of this cap 15 is an outlet nozzle 17, from which the beverage 65

flows into a glass held therebeneath. Snugly fitted in the bore of the casing 12, and extending from the inner end thereof, to the outer end of the flange 14, is the valve member 18, said valve member being cylindrical 70

in shape, and being hollow, as shown, but closed at its opposite ends. In the inner 75 end portion of the valve member 18 there are formed the circularly extending elongated slots 19, which, wholly, or in part, are constantly in registry with the openings 13,

so that a portion of the contents of the container will fill the valve member. The outer end of the flange 14 is formed with a sharp 80 edge 20 with which is engaged the bevel face of the peripheral flange 21, formed on the outer end of the valve member, and whereby

a ground joint is produced, to prevent leakage while the valve member is normally within the bore, and in non-delivering position. Extending centrally from the outer 85

end of the valve member is a stem 22, said stem extending through the opening in the cap 15, and having an ornamental handle 23 secured thereto. In the cap 15, and bearing 90

against the outer wall thereof, and against the flange 21, in encircling relation to the stem 22, is a coil spring 24, which normally 95

and yieldably maintains the valve member 18 at its innermost position in the bore of the casing 12. In the outer end portion of 100

the wall of the valve member 18 there are formed the circularly extending and elongated openings or slots 25, which are adapted to register with the outlet nozzle 17, when 105

the valve member is pulled outwardly, against the tension of the spring 24, whereby 110 to permit the liquid, within said member, to flow into a glass held beneath the nozzle.

It will be particularly noted that the openings or slots 19 are spaced at such a distance 115 from the slots 25 that when the valve member is pulled out a certain distance, the slots 19 will be out of register with the slots 13,

for a short time before the slots 25 register with the nozzle 17, thereby effectively preventing a dishonest clerk holding the valve open and drawing more than a glassful,

which is the amount required to fill the valve member 18.

On the inner end of the valve member 18 there is mounted an agitator, consisting of 5 the radial fan blades 26, which are rigid with respect to the valve member. Upon grasping the handle 23 and turning the valve member within the bore, these blades 26 will stir up the settling or fruit pulp, which has 10 been precipitated to the bottom of the container, so that when the valve member is pulled out, some of these settling will flow out with the beverage. Each time that the valve member is rotated its bevel face at 15 21 will grind against the sharp edge 20, of the flange 14, whereby to maintain a perfect watertight joint, and also to completely cut through any pulp, or solid matter passing out of the valve member and lodging 20 between the said face 21 and edge 20. Thus the act of rotating the valve member serves three purposes, the first to stir up the contents of the container, second to preserve a perfect ground joint, and third to cut 25 through any pulp, or the like which might lodge between the flange 14 and flange 21. It will be noted that the spring 24 maintains the flange of the valve member in positive frictional engagement with the sharp edge 30 of the flange 14, of the container.

It will also be noted that the openings at the inner end of the valve member are so arranged that they will, at all times, register with the openings in the bore wall, either 35 wholly, or in part, so that no matter at what point in the rotation of the said member said member is stopped, liquid will flow into the valve member. Also, the outer openings 25 are so constructed and arranged 40 that they register, wholly, or in part, with the nozzle 17, at any rotatable position of

the member. Thus the rotation of the valve member, to stir up the contents of the container, does not affect the flow of liquid from the container. 45

What is claimed is:

1. The combination with a liquid container having a valve casing extending from the interior thereof through the side thereof, the outer end of the valve casing being 50 surrounded by a flange having a sharp face, a cap secured on the flange, a slideable and rotatable valve member in the bore of the valve casing having a bevel face engaging the said sharp face and a spring in said cap 55 for holding the rotatable member against the first-named bevel face.

2. The combination with a liquid container having a transverse valve casing the inner end portions of the walls of the bore 60 of which are formed with circularly extending and closely spaced elongated slots, a hollow cylinder slideable in said bore and having circularly extending and closely 65 spaced elongated slots normally registering with the first-named slots, the other end of the cylinder having circularly extending and closely spaced elongated slots, a hollow cap secured on the valve casing in covering 70 relation to the outer end of said bore, a peripheral flange on the outer end of the cylinder having a ground fit with the outer 75 end of the wall of the valve casing, said cylinder being adapted to be moved outwardly to register the outer slots with a discharge nozzle formed on said cap and to close the inner slots of the valve casing and cylinder, and resilient means in the cap for retaining the said flange in engagement with the casing wall. 80

In testimony whereof, I affix my signature.

HARRY M. HENDERSON.
